CUSHIONING DEVICE FOR HANDLES

Filed August 4, 1926

INVENTOR.
Charles C. Hansen
BY Herbert G. Odgen
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

CUSHIONING DEVICE FOR HANDLES.

Application filed August 4, 1926. Serial No. 127,161.

This invention relates to crank handles, but more particularly to a cushioning device for the grip portion of a crank handle.

The present invention is particularly applicable to rock drills of the type in which relative longitudinal movement between the drill and its mounting is obtained by means of a feed screw adapted to be manually rotated by means of a suitable crank handle, or for other machines in which excessive vibration is set up during their operation and in which it is necessary for the operator to maintain a constant hold on the crank handle.

15 The objects of the invention are to cushion the grip portion of the crank handle in order to protect the operator's hand against injury which might otherwise be caused by the excessive vibration of the crank handle.

20 Other objects will be in part obvious and in part pointed out hereinafter.

The invention consists of the combination of elements and features of construction substantially as hereinafter described in the 25 appended claims and illustrated in the accompanying drawings, in which

Figure 1 is an elevation of a crank handle equipped with a cushioning device constructed in accordance with the practice of 30 the invention,

Figure 2 is a transverse sectional view taken through Figure 1 on the line 2—2 looking in the direction of the arrows,

Figure 3 is an elevation of a portion of 35 the crank handle equipped with a modified form of cushioning device, and

Figure 4 is a transverse sectional view taken through Figure 3 on the line 4—4 looking in the direction of the arrows.

40 Referring to the drawings, the invention is shown applied to a crank handle A having a bore B for the reception of an end of a feed screw of a rock drill or other similar element (not shown) to which the crank handle A may be applied. The crank handle A in this instance is provided with a lateral grip C having an outer enlarged portion D and a portion E intermediate in the enlarged portion D and the arm F of the 45 crank handle A. The intermediate portion E is in this instance of smaller diameter than the outer portion E as is customary in handles of this type.

50 Means is provided for absorbing the vibration of the crank handle A when the said

crank handle A is used for the purpose of actuating a feed screw of a rock drill or other similar machine in which excessive vibration is set up during the operation of the machine. To this end a yieldable sleeve 60 G, preferably of rubber, is arranged about the grip C which it encircles and is preferably of a length to permit its outer end to extend partly beyond the end of the enlarged portion D of the grip C.

65 In order to enable the sleeve G to rotate freely on the grip C, a ferrule H is inserted in the sleeve G and has an enlarged portion J inclined at its ends as at K and L to engage correspondingly inclined portions of 70 the grip C for preventing relative longitudinal movement between the sleeve G and the grip. A portion O of the ferrule H, of smaller diameter than the portion J, encircles the reduced portion E of the grip C 75 and is preferably of a length to contact with the portion E at a point adjacent the arm F. The ferrule H is in this instance split in half sections P for convenience of assembling same on the grip C and is held in assembled position by the constrictive action of the sleeve G.

80 In assembling the device, the ferrule sections P may first be placed in position on the grip C and the sleeve G may then be 85 telescoped over the sections P. The sections P will thus be held securely in position by the sleeve, since the internal diameter of the sleeve G is preferably slightly smaller than the diameter of the small portion O of 90 the ferrule H.

95 The present invention has been found to be an efficient means for protecting the operator of rock drills and similar machines against the effects of excessive vibration. Heretofore, considerable discomfort has at times been caused to the operator of such machines due to bruises and other injuries caused by the vibratory action of the crank handle. This is particularly true in the operation of certain types of rock drills in which the operator must of necessity maintain a constant grip on the feed screw crank for feeding the drill steel into the rock. This objectionable feature has been entirely eliminated by the present invention and as a result the efficiency of the drill may be considerably increased.

100 In the modification illustrated in Figures 3 and 4, a rubber ferrule or bushing Q is ar- 110

ranged about the reduced portion E of the grip C and is of a length to contact with its ends on inclined surfaces R and S of the grip C to hold the bushing Q against endwise movement with respect to the grip. The bushing Q is preferably split on one side as at T to enable it to be quickly arranged about the grip C.

In the present instance, a sleeve U of suitable length is disposed about the grip C and is preferably of such diameter that when it is in assembled position on the grip C it will be somewhat expanded on the enlarged portion D of the grip C to assist in preventing relative longitudinal movement between the grip and the sleeve.

Any suitable means may be provided for holding the sleeve U and the bushing Q in assembled relationship with respect to each other; in the present instance, rivets V are employed for this purpose and the heads of these rivets are preferably drawn into the sleeve U to prevent contact therewith of the operator's hand.

In assembling the device described in this modification, the bushing Q may first be placed about the grip C and the sleeve U may then be disposed about the said bushing and the grip C. Thereafter the rivets V may be driven through the bushing and the sleeve in such manner that the points of the rivets will be spread on the grip C to

prevent accidental separation of the sleeve and the bushing.

I claim:

1. A cushioning device for a handle, comprising a yieldable sleeve encircling the handle, and means surrounded by the sleeve to engage the handle for preventing endwise movement of the sleeve with respect to the handle, said means being detachable from the sleeve.

2. A cushioning device for a handle having an enlarged portion, comprising a yieldable sleeve encircling the handle, and a ferrule interposed between the handle and the sleeve to engage the enlarged portion for preventing relative longitudinal movement between the handle and the sleeve, said ferrule being held in engagement with the handle by the sleeve.

3. A cushioning device for a handle having an enlarged portion, comprising a yieldable sleeve encircling the handle, and a split ferrule interposed between the handle and the sleeve to engage the enlarged portion for preventing relative longitudinal movement between the handle and the sleeve, said sleeve and said ferrule being freely rotatable on the handle.

In testimony whereof I have signed this specification.

CHARLES C. HANSEN.
